APPARATUS FOR PRESSING TROUSERS
AND OTHER ARTICLESFrederick J. Clark, Buffalo, N. Y., assignor to
Eastman Machine Company, Buffalo, N. Y.

Application October 22, 1934, Serial No. 749,391

14 Claims. (Cl. 68—10)

This invention relates to apparatus for pressing or ironing the seams of trousers' legs or pressing analogous tubular articles requiring pressing at opposite sides of the leg or tube. While the apparatus is particularly suited for the operation of opening out and pressing flat the edges of the inside and outside seams of trousers' legs as is done in the finishing of the trousers, the invention is not restricted to apparatus for this purpose but applies also to apparatus for pressing other articles of tubular shape.

The objects of the invention are to produce a practical and desirable ironing or pressing apparatus suitable for the stated purpose; also to provide a pressing or ironing apparatus of improved construction having a double-faced ironing board or table over which the tubular articles are adapted to be slipped and stretched so as to lie smooth and flat and which is reversible to enable first one side and then the opposite side of the tubular article to be placed uppermost in position for pressing; also to provide an apparatus of the type mentioned which can be quickly and easily operated with the minimum exertion and noise; which will be strong and durable; and which has the other features of advantage and improvement hereinafter described and set forth in the claims.

In the accompanying drawings:

Fig. 1 is a side elevation, partly in longitudinal, vertical section, of a pressing apparatus embodying the invention.

Fig. 2 is a transverse, sectional elevation thereof on line 2—2, Fig. 1.

Figs. 3 and 4 are plan views, on a reduced scale, showing respectively a trousers' leg on the ironing board before and after stretching the leg.

Figs. 5 and 6 are transverse sections of the ironing board on an enlarged scale on lines 5—5 and 6—6 respectively, Fig. 1.

Fig. 7 is a sectional plan view of the apparatus on line 7—7, Fig. 1.

Fig. 8 is a sectional plan view of the ironing board or table and article stretching mechanism.

Fig. 9 is a longitudinal, sectional view on an enlarged scale on line 9—9, Fig. 1.

Fig. 10 is a transverse sectional elevation on an enlarged scale on line 10—10, Fig. 9.

Fig. 11 is a transverse, sectional elevation on line 11—11, Fig. 1, showing the mechanism for reversing the ironing board.

Fig. 12 is a transverse sectional elevation on line 12—12, Fig. 1, showing the treadle operating mechanism for the article stretching means.

Figs. 13, 14 and 15 are sectional elevations of

the ratchet mechanism for reversing the ironing board, showing different positions of the parts thereof.

Fig. 16 is a sectional plan view on line 16—16, Fig. 11.

The apparatus illustrated in the drawings comprises a double-faced ironing board or pressing table 20 over which the tubular article to be pressed is slipped endwise and which is mounted so that it can be inverted to place either of its opposite faces uppermost, means for stretching the tubular article smooth on the pressing table, operating mechanism for the stretching means, and operating mechanism for reversing the pressing table.

Preferably the pressing table consists of two parallel ironing boards 21 which are secured together face to face in spaced-apart relation, by U-shaped brackets 22 between and to which the two boards are suitably fastened, as by screws. Rigid with and extending lengthwise from one end of the pressing table is a supporting spindle or tube 23 which is rotatably mounted in suitable spaced bearings 24 and 25 on a stationary supporting frame which, as shown, has a hollow portion 26 which rises from one end of a horizontal base 27 and supports a separate cover or housing 26a enclosing said bearings. The base 27 extends horizontally beneath the pressing table and is adapted to rest on and be secured to the floor. In the preferred construction shown, a metal channel bar 28 is rigidly attached at its inner end to the outer end of the spindle 23 and extends therefrom lengthwise between the spaced ironing boards, this channel bar being bolted or otherwise rigidly fastened to one of the ironing boards 21 and to the spacing brackets 22 for the boards, whereby the two boards are rigidly secured to the channel bar 28 and, through the medium of the latter, to the supporting spindle 23. Thus, the pressing table, while being rotatably or reversibly mounted at one end only thereof, is nevertheless firmly supported so that its overhanging outer end will not sag or deflect appreciably in the use of the apparatus.

The supporting spindle 23 is turned in its supporting bearings 24 and 25 for reversing the pressing table to place one or the other ironing board uppermost in pressing position, preferably by treadle-actuated mechanism constructed as follows:

Fixed to the spindle 23, within the housing 26a is a toothed gear pinion 30 which meshes with a gear wheel 31 rotatable on a stud axle 32 which is fixed on and projects from the bracket 33 of

the spindle bearing 25. The pinion 30 shown has thirty teeth, and the gear wheel 31 has seventy-five teeth, so that by a one-fifth revolution of the gear wheel 31, the pinion 30 is turned one-half of a revolution for turning the pressing table from a position in which one ironing board 21 faces upwardly to a position in which the other ironing board 21 is placed face upward. The gear wheel 31 is rotated for this purpose by a ratchet mechanism comprising a ratchet wheel 34 bolted or otherwise fixed to the gear wheel 31, a pawl 35 which is adapted to engage in peripheral notches in the ratchet wheel 34 and is pivoted on a pawl lever or carrier 36 journalled to rock on the stud axle 32. The pawl lever is connected by a rod or link 37 to an arm 38 fixed on a horizontal treadle shaft 39 which extends lengthwise over the base 27 of the machine and is journalled near its opposite ends in suitable bearings 40, 41 on the base. The rod 37 is suitably pivoted at its opposite ends to the pawl lever and to the arm 38. This ratchet mechanism is enclosed within the frame housing 26a of the frame. A treadle 42 is fixed to the treadle shaft 39 at its outer end portion, preferably in engagement with the inner end of the outer bearing 41 for the treadle shaft so as to prevent outward endwise movement of the treadle shaft, which is prevented from opposite endwise movement by a collar on the shaft engaging the inner end of the inner bearing 40. By depressing the outer end of the treadle 42, which projects forwardly in convenient reach of the foot of the operator standing in front of the machine, the pawl lever is swung through an arc sufficient to rotate the gear wheel 31 one-fifth of a revolution.

In order to limit the extent of the turning movement of the gear wheel 31 and to hold the pressing table with one or the other of the two ironing boards in horizontal position suitable for pressing the article thereon, a lock or dog 45 is provided which is suitably pivoted at 46 on the bearing bracket 33 and is provided at its free end with a tooth adapted to enter one or another of the peripheral notches 47 in the ratchet wheel 34. The toothed free end of the dog 45 is held by a spring 48 against and adapted to ride on the circular periphery of the ratchet wheel 34, and when the ratchet wheel has been turned by its operating mechanism to a position to place either of the ironing boards horizontally upward, the tooth of the dog will be opposite to, and will be projected by the dog spring into one of the notches of the ratchet wheel, as shown in Figs. 1 and 13. In this position of the parts, the tooth of the dog 45 by engagement in the notch of the ratchet wheel, will hold the ratchet wheel, and therefore the connected gear and pressing table stationary, and against turning in either direction. At this time the pawl, pawl lever and treadle 42 will be in the raised positions shown in Figs. 1 and 13.

When the treadle 42 is depressed for reversing the pressing table, during the first portion of the downward movement of the treadle, the pawl lever 36 and pawl 35 will move independently of, or relatively to the ratchet wheel, until the pawl fully enters the adjacent notch of the ratchet wheel. This free movement of the pawl lever is sufficient for a trip projection 49 on the pivoted end of the pawl lever 36 to engage the inner free end of a trigger 50 pivoted at 51 on the dog 45, and press this trigger against a stop pin 52 on the dog, thereby swinging the dog out of engagement with the notch in the ratchet wheel. The

trip projection 49 will then pass out of engagement with the end of the trigger, permitting the continued downward movement of the pawl lever for turning the ratchet wheel, until the dog is moved by its spring into the next notch of the ratchet wheel and arrests the ratchet wheel with the pressing table in the inverted position, in which position the pressing table will be locked by the engagement of the locking dog in the notch of the ratchet wheel. The trip projection 49 preferably consists of a plate adjustably secured, as by screws 49a, on a lug on the pawl lever, thus permitting adjustment of the trip plate relatively to the trigger to insure correct coaction of these parts. When the depressed treadle 42 is released, it will be raised or returned to its normal position by a counterweight 53 on the pawl lever at the opposite side of the lever pivoted from the pawl. In the return movement of the treadle the trip plate 49 will strike the opposite side of the inner end of the trigger 50 and tilt the trigger on its pivotal connection with the dog sufficiently to permit the trip plate to pass by the trigger without moving the dog, which remains in engagement with the notch in the ratchet wheel, thereby holding the same and the pressing table with which the ratchet wheel is connected, stationary and in the position to which it was moved by the depression of the treadle. Thus, it is not necessary to hold the treadle down by the pressure of the foot thereon in order to hold the pressing table stationary, but it is simply necessary to depress the treadle until the movement of the ratchet wheel and pressing table is arrested and locked by the engagement of the dog 45 with the next notch in the ratchet wheel.

In the use of the apparatus for opening and pressing flat the seams of trousers' legs, one leg of the trousers, which have been turned wrong side out, is slipped onto the pressing table over the free end thereof, with one seam facing upwardly, as shown in Figs. 3 and 4, and the trousers' leg is stretched or expanded to lie smooth on the pressing table by the leg stretching means. These means comprise two stretching bars 60 extending along opposite edges of the pressing table to move laterally in and out between the spaced ironing boards 21. The stretching bars 60 are movably supported by link mechanism, being, as shown pivoted adjacent their inner end portions to the outer ends of a pair of links 61 which are pivoted at their inner ends to a slide block 62 movable longitudinally in the channel bar 28, and adjacent their outer ends, each stretching bar being pivoted to the outer ends of oppositely inclined or toggle links 63, 64. Links 63 are pivoted at their inner ends to a slide block 65 and the links 64 are pivoted at their inner ends to a stationary block or part 66. The slide block 65 is arranged to slide lengthwise in the channel bar 28 while the block 66 is fixed to the channel bar. The links 61, 63 and 64 are moved to spread and contract the stretcher bars by a rod 67 which extends lengthwise through the pressing table and its spindle. Preferably, this rod passes through holes in the lugs on the blocks 62, 65 and 66 and is movable lengthwise in the central bore of the spindle 23. The slide block 62 is fixed, as by a set screw, to the rod and moves with the rod, and a spring 68 surrounds the rod 67 between the slide block 65 and a collar 69 fixed on the rod 67. By moving the rod 67 outwardly, the block 62, fixed to the rod, will spread the links 61 and inner ends of the stretcher bars, 75

and the spring 68 will be compressed and move the slide block 65 and links 63 and 64 to spread the outer ends of the stretcher bars apart for stretching the outer end of the trousers' leg on the pressing table. This spreading means enables equalization of the pressure of the stretching bars on the upper and lower or thigh and ankle portions of the trousers' leg so as to evenly stretch the leg on the pressing table as well as automatically accommodating itself to legs of different widths and different tapers. 70 indicates a spring surrounding the rod 67 between the block 62 and the end of the spindle for cushioning the inward or retracting movement of the rod 67 and stretching bars 60.

The rod 67 is shifted lengthwise to spread and contract the stretcher bars, preferably by a treadle actuated mechanism constructed as follows:

75 represents a treadle which is fixed on the outer end of a tubular shaft or sleeve 76 which surrounds the treadle shaft 39, and is suitably mounted to rock, as in bearings 77, on the machine base 21. An arm 78, fixed to the inner end 25 of the tubular shaft 76 is connected by a rod or link 79 to a lateral arm 80 of a bell crank lever which is suitably pivoted within the housing 26a of the stationary frame. An up-standing arm 81 of this lever has a forked upper 30 end having a pin and slot connection with a collar 82 surrounding the spindle 23 of the pressing table and adapted to be slid along said spindle by depressing the treadle 75. Slidable within the hollow spindle 23 and fixed on the stretcher rod 35 67 is a collar 83 which is provided with studs 84 projecting through longitudinal slots 85 in the spindle into an internal annular groove 86 in the outer collar 82. Thus, the inner collar is adapted to be slid lengthwise in the hollow spindle by longitudinal movement of the outer collar 82 while nevertheless the spindle with the inner collar is adapted to revolve in the outer collar. The rod 67 is thus adapted to be moved longitudinally for spreading the stretcher bars by depressing the treadle 75. A counterweight 87 connected to a third arm 89 of the bell crank lever is provided for raising or returning the treadle and the connected mechanism to their normal positions when the treadle is released.

50 In order to hold the trousers' leg stretched by the stretching mechanism while pressing the seam, without requiring the operator to hold down the treadle 75 by the pressure of his foot thereon, a holding device 90 for the treadle 75 is provided. This holding device preferably consists of a lever suitably pivoted at its lower end on the base 21 of the stationary frame adjacent the treadle 75 and having an arm extending upwardly adjacent the treadle 75 and provided with 55 ratchet teeth 91 arranged to engage a projection 92 on the treadle 75. This projection is adapted to engage with one or another of the teeth 91 for holding the treadle depressed to different extents, as may be necessary, to properly stretch different trousers' legs. The ratchet arm is releasably held in engagement with the projection of the treadle by a spring 93 arranged between the frame base 21 and a foot or treadle plate 94 on the holding device. This treadle plate 60 projects forwardly in a position to be conveniently operated by the operator's foot for moving the holding device to release the treadle 75. When the treadle 75 is depressed, it will be held down by the ratchet holding device 90, and when it 65 is desired to release the treadle to remove the

stretching pressure on the trousers' leg, it is simply necessary to press slightly on the treadle plate of the holding device to thereby release the treadle 75 and permit the return of the same to its normal raised position.

70 95 represents a shock absorber for reducing shock, wear and noise in the operation of the apparatus. This device preferably consists of a hydraulic shock absorber of well known type comprising a casing and a movable piston or member 10 therein, the movement of which is retarded or checked, as required, to suit the intended purpose of the device by suitably controlling the flow of liquid which opposes motion of the movable member. As shown, the casing of this shock absorber is fixed on the supporting bracket of the treadle shaft bearing 40, and a swinging arm 96, which moves with the piston, is connected as by a link 97, to the rocker arm 38 of the treadle actuated table reversing mechanism. 15 This shock absorber is adapted to cushion or check the motion of the treadle at the finish of its downward movement for reversing the pressing table, and when the treadle is released and the reversing mechanism is returned to its initial 20 position by the counterweight 53, the shock absorber is adapted to similarly check or cushion the motion of the mechanism at the finish of its return movement. The pressing table is thus adapted to be reversed by a quick depression of 25 the treadle, which can be easily moved by the foot of the operator, but the motion of the mechanism at the finish of its operative and return movements is adapted to be cushioned by the shock absorber so as to prevent undue shock, 30 strain and wear on the table lock and reversing mechanism and reduce the noise of operation of the apparatus to the minimum.

The apparatus shown is provided with a shelf or table 98 stationarily secured to the frame and 40 extending beneath the pressing table for supporting portions of the articles being pressed which may hang down from the pressing table and thereby hold them from contact with the floor.

45 I claim as my invention:

1. The combination of a pressing table having opposite pressing surfaces and reversibly mounted for placing either of said surfaces uppermost, a locking device operating to hold said pressing table stationary with either of its pressing surfaces uppermost, and reversing mechanism for said pressing table which when operated releases said locking device to permit the reversal of the 55 pressing table.

2. The combination of a pressing table having opposite pressing surfaces and reversibly mounted for placing either of said surfaces uppermost, a locking device for holding said pressing table in each of its reversible positions, a treadle, and mechanism operated by said treadle for actuating said locking device to release the table and for reversing said table.

3. The combination of a pressing table having opposite pressing surfaces and reversibly mounted for placing either of said surfaces uppermost, a ratchet mechanism comprising a ratchet wheel operatively connected with said table for reversing the table by turning said ratchet wheel, a locking device cooperating with said ratchet wheel for holding said table stationary in each of its reversible positions, and operating mechanism which actuates said locking device to release said ratchet wheel and turns said ratchet wheel for reversing the table.

4. The combination of a pressing table having opposite pressing surfaces and reversibly mounted for placing either of said surfaces uppermost, ratchet mechanism for reversing said pressing table, a locking device cooperating with said ratchet mechanism for holding said table stationary in each of its reversible positions, an operating device for said ratchet mechanism, and means actuated by said operating device to move said locking device to release said ratchet mechanism when said operating device is actuated to operate said ratchet mechanism for reversing the table.
5. The combination of a pressing table having opposite pressing surfaces and reversibly mounted for placing either of said surfaces uppermost, ratchet mechanism for reversing said pressing table, a locking device cooperating with said ratchet mechanism for holding said table stationary in each of its reversible positions, a treadle and connections for operating said locking device to release said ratchet mechanism and for operating said ratchet mechanism for reversing said pressing table.
10. The combination of a pressing table having opposite pressing surfaces and reversibly mounted for placing either of said surfaces uppermost, a treadle shaft, a tubular shaft surrounding said treadle shaft, a treadle on each of said shafts for rocking the shaft, mechanism operated by rocking one shaft for stretching the article on said pressing table, and mechanism operated by rocking said other shaft for reversing the pressing table.
15. The combination of a pressing table having opposite pressing surfaces and reversibly mounted for placing either of said surfaces uppermost, a treadle, mechanism carried by the pressing table and actuated by said treadle for stretching a tubular article on said pressing table in either pressing position of the table, a treadle released holding device for said treadle, another treadle, and mechanism actuated thereby for reversing said pressing table.
20. The combination of a pressing table having opposite pressing surfaces and reversibly mounted for placing either of said surfaces uppermost, a treadle, mechanism carried by the pressing table and actuated by said treadle for stretching a tubular article on said pressing table in either pressing position of the table, a treadle released holding device for said treadle, another treadle, and mechanism actuated thereby for reversing said pressing table.
25. The combination of a pressing table having opposite pressing surfaces and reversibly mounted for placing either of said surfaces uppermost, a ratchet wheel geared to said pressing table, a pawl for turning said ratchet wheel, a locking device for holding said ratchet wheel from turning, and operating means for actuating said locking device to release said ratchet wheel and for actuating said pawl to turn said ratchet wheel for reversing said pressing table.
30. The combination of a pressing table having opposite pressing surfaces and reversibly mounted for placing either of said surfaces uppermost, a ratchet wheel geared to said pressing table, a pawl for turning said ratchet wheel, a carrier for said pawl, a locking device for holding said ratchet wheel from turning, means for operating said pawl carrier for turning said ratchet wheel, and cooperating parts on said pawl carrier and locking device operating to release said locking device when said pawl carrier is actuated by turning said ratchet wheel.
35. The combination of a pressing table having opposite pressing surfaces and reversibly mounted for placing either of said surfaces uppermost, a ratchet wheel geared to said pressing table, a pawl for turning said ratchet wheel, a carrier for said pawl, a locking device for holding said ratchet wheel from turning, means for operating said pawl carrier for turning said ratchet wheel, and cooperating parts on said pawl carrier and locking device operating to release said locking device when said pawl carrier is actuated by turning said ratchet wheel.
40. The combination of a pressing table having opposite pressing surfaces and reversibly mounted for placing either of said surfaces uppermost, a treadle, mechanism carried by said reversible table and actuated by said treadle for stretching a tubular article on said pressing table in either pressing position of the table, and treadle actuated means for reversing said pressing table to place either of its pressing surfaces uppermost.
45. The combination of a pressing table having opposite pressing surfaces and reversibly mounted for placing either of said surfaces uppermost, two adjacent treadles, mechanism carried by said reversible table and actuated by one treadle for stretching an article on said pressing table in either pressing position of the table, and treadle actuated means for reversing said pressing table to place either of its pressing surfaces uppermost.
50. The combination of a pressing table having opposite pressing surfaces and reversibly mounted for placing either of said surfaces uppermost, treadle actuated mechanism for reversing said pressing table, a locking device for stopping the reversing movement of and releasably holding said table stationary with either pressing surface uppermost, and a shock absorber operatively connected with said treadle mechanism for retarding the motion of said treadle actuated mechanism at the finish of its return movement.
55. The combination of a pressing table having opposite pressing surfaces and reversibly mounted for placing either of said surfaces uppermost, treadle actuated mechanism for reversing said pressing table, a locking device for stopping the reversing movement of the pressing table and for releasably holding said table stationary with either pressing surface uppermost, means for returning said treadle mechanism when released to its initial position, and a shock absorber cooperating with said treadle actuated mechanism to retard the motion of the treadle mechanism at the finish of its operative and return movements.
60. The combination of a pressing table having opposite pressing surfaces and reversibly mounted for placing either of said surfaces uppermost, treadle actuated mechanism for reversing said pressing table, a locking device for stopping the reversing movement of the pressing table and for releasably holding said table stationary with either pressing surface uppermost, means for returning said treadle mechanism when released to its initial position, and a shock absorber cooperating with said treadle actuated mechanism to retard the motion of the treadle mechanism at the finish of its operative and return movements.

FREDERICK J. CLARK. 60
